UNITED STATES PATENT OFFICE

142,531

DESIGN FOR A WEED PULLER

Robert T. Sand, Detroit, Mich.

Application May 17, 1945, Serial No. 119,589

Term of patent 14 years

(Cl. D35—2)

To all whom it may concern:

Be it known that I, Robert T. Sand, a citizen of the United States, residing at Detroit, in the county of Wayne and State of Michigan, have invented a new, original, and ornamental Design for Weed Puller, of which the following is a specification, reference being had to the accompanying drawing, forming part thereof.

In the drawing:

Fig. 1 is a plan view of a weed puller showing my new design; and

Fig. 2 is a side elevational view thereof.

I claim:

The ornamental design for a weed puller, as shown.

ROBERT T. SAND.
